R. A. MOORE,
LIQUID AGITATING DEVICE,
APPLICATION FILED APR. 21, 1914.

1,151,372.

Patented Aug. 24, 1915.

UNITED STATES PATENT OFFICE.

ROBERT A. MOORE, OF NEW YORK, N. Y., ASSIGNOR, BY DIRECT AND MESNE ASSIGNMENTS, TO MOORE-LIBBY SPECIALTIES COMPANY, INCORPORATED.

LIQUID-AGITATING DEVICE.

1,151,372.

Specification of Letters Patent. Patented Aug. 24, 1915.

Application filed April 21, 1914. Serial No. 833,495.

To all whom it may concern:

Be it known that I, ROBERT A. MOORE, a citizen of the United States, residing at New York, in the county of New York and State 5 of New York, have invented certain new and useful Improvements in Liquid-Agitating Devices, of which the following is a specification.

This invention appertains to improvements in a common type of egg beaters or similar agitating devices wherein coacting agitating members are rotated at high speed in opposite directions under the action of suitable driving means consisting usually of 15 a gear meshing with pinions on certain shafts which directly support said agitating members.

My primary object in devising the present improvements has been to provide agitating 20 means of peculiar form whereby to more thoroughly break up or agitate the fluid or substance operated on by the beater, than is practicable in the use of similar devices heretofore employed. With this in view I 25 utilize agitating means comprising frames rotatable in different paths though fairly close proximity, each frame consisting of a piece of metal not only bent peculiarly to afford a maximum amount of agitating surface but, of greater importance, formed with 30 specially arranged corrugations or deflected portions adapted to positively throw the liquid or other substance to be agitated in opposite directions from the frame in paths 35 intersecting the paths of movement of the adjacent agitating frame. In fact, in actual practice the agitating frames in acting on the liquid tend to throw the portions of the latter in intersecting paths and in this 40 way a very high degree of efficiency is obtained in breaking up the liquid, so to speak, to secure the greatest possible agitating effect.

Another primary object of my invention 45 has been to provide a beater or similar agitating device for various purposes, the construction of which is so simple as to be exceedingly cheap to manufacture, practically all of the operating parts being capable of 50 being stamped out of metal.

A third important object of the invention has been to so devise the agitating contrivance as to facilitate the separation of the various parts thereof for purposes of

cleaning, and admitting of very quick re- 55 placement in coöperative relation.

With the above and other objects in view the advantages of the invention will be fully appreciated on reference to the following detailed description and to the accompanying drawing in which:

Figure 1 is a side view of a device embodying the essential features of the invention. Fig. 2 is a vertical sectional view on the line 2-2 of Fig. 1. Fig. 3 is a plan view of the 65 blank piece of metal from which the handle is formed. Figs. 4 and 5 are perspective and sectional views respectively, showing more clearly the method of forming the corrugated or deflecting elements of the agi- 70 tating members. Fig. 6 is a section on the line 6-6 of Fig. 1.

In the drawings A denotes the shank or body of the egg beater, B the handle, and C and D the agitating members or frames. 75 The shank A is preferably made from a piece of sheet metal the lower end of which is bent laterally to form a bearing arm 1 and there being three other arms 2, 3 and 4, bent outward from the body of the shank. 80 The arms 2, 3 and 4 are preferably made by cutting the shank A and then striking out the cut portions as seen clearly in Figs. 1 and 2. The arm 2 is adjacent the upper end of the shank and forms a stop as well as 85 bearing for the upper end of a solid shaft 5 which is supported in bearing openings formed in the arms 1, 3 and 4. The solid shaft does not directly engage the arms 1 and 4, however, being adapted to rotate in a 90 hollow shaft 6 which is supported in the bearing openings of said arms 1 and 4. The shaft 5 projects some distance beyond the lower end of the shank A and rigidly attached thereto, is the agitating member or 95 frame D above referred to. On the other hand the hollow shaft 6 extends from a point adjacent the arm 4 and a slight distance beyond the arm 1 sufficient to permit the attachment thereto for rotation of the 100 other agitating member C. The lower end of the shaft 5 not only passes through the lower end of the agitating member D but also through the corresponding end of the agitating member C which is larger than the member D and rotates in a path spaced from and surrounding the path in which the member D rotates.

It is contemplated to employ a drive gear E for operating the members C and D, said gear E being preferably formed with openings arranged annularly thereof, in which openings the teeth of pinions 7 and 8 engage, the pinion 7 being carried by the shaft 5 and the pinion 8 by the hollow shaft 6. Said shafts 5 and 6 are preferably formed with longitudinal grooves and the pinions are provided with integral projections or key elements seated in the grooves of the respective shafts to fix the pinions upon said shafts for rotation therewith. The gear E is mounted on a stud 9 as an axis and when being rotated by the handle 10 the movement of the gear E is transmitted to the pinions 7 and 8, their respective shafts 5 and 6 and the respective agitating members D and C carried by said shafts. In this way the agitating members C and D may be rotated at high speed in opposite directions and in non-intersecting paths, the operator grasping the handle B in one hand and turning the gear E through the medium of the handle 10 grasped by the other hand. The formation of the agitating members C and D is especially important, as before premised, each member consisting of a frame made from a strip of metal arranged horizontally edgewise but formed at close intervals with oppositely inclined corrugations 11. The corrugations 11 have a unique action during the rotation of the members C and D in the fluid or mixture to be agitated. Since certain alternate corrugations incline in the same direction and the intermediate corrugations are oppositely inclined it follows that while each agitating member is rotating, portions of the fluid agitated are forcibly thrown at an angle to the general horizontal path in which the member rotates and in directions both upward and downward in respect to said path. In this way not only do the elements 11 of each of the members C and D cause the liquid agitated to be thrown in paths intersecting the parts of each member itself, but also into paths in which said portions of the liquid are caused to impinge one another by intersecting, so to speak, the liquid being thoroughly broken up with a maximum agitation under such conditions.

The above result is subserved owing to the fact that the upper and lower portions of each agitating member C and D are connected by the sides of each member, which sides are formed of a plurality of recurved portions of the metal from which the parts are made. In other words, the sides of each member C and D curve inwardly and outwardly a number of times, the curvatures of said sides corresponding.

I provide a very simple and advantageous handle member B also made out of sheet metal, with a view of reducing the cost of

manufacture of my whole contrivance. The blank from which the handle B is made in Fig. 3 and is composed of the body portion which forms the handle proper, and end portions of T-form provided with ears b which are bent toward one another so as to embrace therebetween the upper end of the shank A. These end portions of the handle B are interlocked with the shank A owing to the method of bending the ears b into engagement with the shank under high pressure, portions of the ears b being bent into the cut-away portion from which the arm 2 is struck out from the body of the shank.

When it is desired to separate the parts of the device for thorough cleaning, a small pin 12 passing through the shaft 5 at a point above the pinion 7 is removed and the members C and D may be pulled off of the shank A with their respective shafts. The pinions 7 and 8 will of course be thus separated from the shafts, said pinions normally operating in the clearance spaces afforded by the method of striking out metal of the shank A to provide the arms 3 and 4. A most sanitary and effective device is provided owing to the foregoing advantageous separability of the parts which may be just as conveniently replaced in their operative positions in an obvious manner.

Having thus described the invention, what is claimed as new is:—

1. In an egg beater or the like, the combination of a shank consisting of a piece of sheet metal having its lower end bent to form a lateral arm and provided intermediate its ends with struck-out portions forming other bearing arms and a stop arm, a gear rotatable on said shank, a shaft having one end engaged with said stop arm and passing through the other bearing arms, a hollow shaft mounted in certain of said bearing arms and having the first mentioned shaft passing therethrough, agitating members carried by said shafts at corresponding ends of the latter, pinions mounted on said shafts in spaced relation at the other corresponding ends of the same and engaging with said gear at portions of the latter on opposite sides of its axis, means for preventing displacement of said shafts from the shank, and a handle carried by said shank.

2. In an egg beater or the like, the combination of a shank consisting of a piece of sheet metal having its lower end bent to form a lateral arm and provided intermediate its ends with struck-out portions forming other bearing arms and a stop arm, a gear rotatable on said shank, a shaft having one end engaged with said stop arm and passing through the other bearing arms, a hollow shaft mounted in certain of said bearing arms and having the first mentioned shaft passing therethrough, agitating mem-

bers carried by said shafts at corresponding ends of the latter, pinions mounted on said shafts in spaced relation at the other corresponding ends of the same and engaging 5 with said gear at portions of the latter on opposite sides of its axis, means for preventing displacement of said shafts from the shank, and a handle carried by said shank, said handle consisting of a length of 10 sheet metal formed with oppositely extending lateral ears at each end, said ears being bent to embrace one end of the shank and interlocking with the same.

3. Agitating means of the class described 15 comprising spaced revoluble agitating members, each member consisting of a strip formed with a plurality of rebent superposed portions so as to constitute a series of parallel horizontally extending agitating 20 elements, the edge of the strip at one side of a horizontal element being corrugated and at its opposite edge likewise corrugated but at intermediate transverse points whereby to form staggered corrugations, and the staggering arrangement being oppositely formed with respect to adjacent horizontal 25 elements to throw liquid impinged thereby in intersecting streams.

4. Agitating means of the class described 30 comprising spaced revoluble agitating members, each member consisting of a strip formed with a plurality of rebent superposed portions so as to constitute a series of parallel horizontally extending agitating

elements, the edge of a strip at one side of a 35 horizontal element being formed with corrugations forming alternate ridges extending above and below the horizontal plane of movement of the strip in revolving, and its other edge being likewise ridged but in diametrically opposite directions to the corresponding ridges first mentioned, and the corrugations of adjacent horizontal elements being staggeredly arranged whereby each 40 element will throw upwardly and downwardly directed streams of liquid impinged thereby adapted to intersect correspondingly 45 directed streams of an adjacent element.

5. Agitating means of the class described comprising agitating members revoluble 50 about a common axis, said members consisting of an outer and inner frame, each frame having its sides correspondingly bent inwardly a plurality of times to form spaced substantially parallel re-curved portions extending at right angles to the axis of rotation of said frames, the re-curved portions of said frames being formed with liquid impinging corrugations arranged oppositely 55 with respect to each other whereby to throw 60 the liquid in streams of intersecting paths, and means for rotating the frames.

In testimony whereof I affix my signature in presence of two witnesses.

ROBERT A. MOORE.
